CLAIM

The ornamental design for a nucleic acid sequencing system display screen with a graphical user interface, as shown and described.

DESCRIPTION

FIG. 1 illustrates a front view of a first embodiment of a nucleic acid sequencing system display screen with a graphical user interface of our new design;

FIG. 2 illustrates a front view of a second embodiment of a nucleic acid sequencing system display screen with a graphical user interface of our new design;

FIG. 3 illustrates a front view of a third embodiment of a nucleic acid sequencing system display screen with a graphical user interface of our new design;

FIG. 4 illustrates a front view of a fourth embodiment of a nucleic acid sequencing system display screen with a graphical user interface of our new design;

FIG. 5 illustrates a front view of a fifth embodiment of a nucleic acid sequencing system display screen with a graphical user interface of our new design;

FIG. 6 illustrates a front view of a sixth embodiment of a nucleic acid sequencing system display screen with a graphical user interface of our new design;

FIG. 7 illustrates a front view of a seventh embodiment of a nucleic acid sequencing system display screen with a graphical user interface of our new design; and,

FIG. 8 illustrates a front view of an eighth embodiment of a nucleic acid sequencing system display screen with a graphical user interface of our new design.

The broken line at the perimeter of the figure illustrates the display screen and the remaining broken lines illustrate portions of the graphical user interface. None of the broken lines form any part of the claimed design.

1 Claim, 8 Drawing Sheets
